UNITED STATES PATENT OFFICE

HAROLD B. WOODS, OF HUDSON, MASSACHUSETTS, ASSIGNOR, BY MESNE ASSIGNMENTS, TO CONSOLIDATED AUTOMATIC MERCHANDISING CORPORATION, A CORPORATION OF DELAWARE

ENVELOPE-DISPENSING MACHINE

Application filed January 8, 1927. Serial No. 159,967.

This invention relates to means and methods of dispensing envelopes singly, where the dispensing means is released by coin controlled means, which normally prevents operation of the dispensing means.

It is considered that the most practical method of dispensing envelopes is to deliver them successively from the bottom of a stack thereof, and certain machines, which have been designed to operate in this manner, have the envelopes stacked therein, flap down, and have means to engage the envelope at the bottom of the fold between its flap and its body and push it from beneath the stack. While this arrangement may operate satisfactorily under certain conditions, if the air becomes moist, the gummed portion of the flap is liable to adhere to the body part, so that, when the separating device is operated to pass inside the flap, it will be prevented from so doing.

Also, much difficulty has been encountered in producing an envelope dispensing machine which cannot be pilfered thru the envelope delivery opening.

The objects of my invention are to provide a method of dispensing envelopes singly from a stack, and a machine which will effectively operate in accordance with such method, whereby the delivery of an envelope without mutilation thereof will be insured, regardless of the fact that the envelope flap may have become partly or wholly adhered to the envelope body throughout its gummed surface. Also to provide a machine which cannot be pilfered thru the delivery opening, and which is positive in action and simple in construction.

I accomplish these objects in the manner hereinafter described and as illustrated in the accompanying drawing in which:

Fig. 1 is a front elevation of a casing of a machine embodying the invention.

Fig. 2 is a rear elevation thereof with the rear wall removed.

Fig. 3 is a sectional plan view at line 3—3 of Fig. 1.

Fig. 4 is a vertical sectional view at line 4—4 of Fig. 1.

Figs. 5 and 6 are detail sectional views at line 5—5 of Fig. 1 on an enlarged scale.

Fig. 7 is a detail sectional view illustrating the action of the follower.

Figs. 8, 9 and 13 are detail views illustrating the action of the separator fingers, and

Fig. 12 is a perspective view of one of said fingers.

Figs. 10 and 11 are detail views of a coin intercepting device which is employed.

As shown in the drawing, the outer casing has vertical front, side and rear walls arranged at right angles to each other, the front wall 1 having a coin slot 2 therein and a coin return cup 3, at its bottom, and a chamber 4 being provided in one end to receive the coin controlled mechanism, not shown. The inner wall 5 of chamber 4 forms one end wall of the envelope magazine, which is provided within the casing, the opposite end wall being partly formed by the outer casing wall 6 and partly by an inwardly and downwardly inclined inner partition 7. The rear wall 8 of the casing forms the rear wall of the magazine and the top is closed by a cover 9 which may be made removable for filling purposes. The bottom 11 of the magazine is rectangularly shaped to correspond with the envelopes to be dispensed and is horizontally arranged at a level to permit a stack of envelopes of suitable height to be placed in the machine.

The front wall 1 of the casing has a rectangularly shaped opening in which two plate sections 12 and 13, of corresponding shape, are secured to close the same, the adjacent horizontal edges of said sections being arranged to provide an envelope delivery slot 14 therebetween of a length and height just sufficient to permit a single envelope only to pass edgewise therethru. The middle portions of said plate sections have semi-elliptically shaped protuberances on their rear sides, at the middle portions of their adjacent edges, which are recessed from the front and together form a single depression, or recess 15, in the middle portion of the slot 14, the space provided by said recess at each side of the slot being sufficient to permit insertion of the fingers of the operator, so as to grasp the

edge portion of an envelope which has been passed into the portion of the slot which extends thru the recess, so as to draw the envelope out thru the slot, as hereinafter explained.

5 The upper plate section 13 has a horizontal flange 16 formed integrally therewith, and which extends rearward from the inner side thereof, with its lower side at the level of the 10 upper side of the slot 14, and meets the lower edge of a vertical partition 10, which is fixed within the casing and forms the front side of the magazine. The lower section 12 has a similar flange 17, which extends rearwardly 15 therefrom in parallel relation to flange 16, with its upper surface at the level of the under side of slot 14 and of the bottom 11 of the magazine, so that it practically forms an extension of the latter, said flanges 16 and 17 20 thus forming a guide passage for the envelope which extends from the magazine to the discharge slot. The height of the middle portion of the entrance to said passage from the magazine is such that the entrance there- 25 to of more than a single envelope of maximum thickness at one time is prevented, and adjustable stop fingers 18 may be provided on the inner side of the partition 10 to reduce the height of said passage in case the envelope 30 to be dispensed is of less thickness than normal. The under surface of the upper guide flange 16 has upwardly inclined portions 16^a, which extend from the horizontal middle portion thereof, at each side, to horizontal end portions 16^b, the latter extending to depending edge ribs 16^c, the inner sides of which act as guide faces for the envelopes when dispensed, as shown in Figs. 2 and 13.

35 The separator device, for removing the bottom envelope of the stack and delivering it to the operator of the machine, comprises a flat plate 20, which is slidably mounted in guide ways 21 secured to the under side of the bottom 11, and arranged to carry the plate to 40 and from the front side of the machine, a rod 22, having a handle 23 at its outer end, being connected to plate 20 and extending thru the front wall section 12. The bottom 11 is extended the full length of the envelopes at its 45 rear portion, and is notched, or reduced in length at each end and at its front portion, to receive fingers 24, which are formed integrally with the separator plate 20 and extended upwardly therefrom in close prox- 50 imity to the notched ends of the bottom, and then horizontally towards the front wall at a level slightly above that of the top surface of the bottom, so that the vertical distance between the underside of the fingers and said 55 surface is as great as, or slightly greater than the thickness of the envelope flap. The side edges of said fingers are parallel to the adjacent end edges of the bottom and are held in close proximity thereto, the width of said 60 fingers corresponding to the extent to which 65

the bottom is notched. The front edges 24^a of said fingers are perpendicular to their sides and are arranged in alignment and are dulled or rounded, so that they will not cut the envelopes. The adjacent or inner corners of the fingers are rounded and beveled on their undersides to a sharp edge, to form wedging portions 24^b, as shown in Fig. 12.

70 A follower is provided for the envelopes in the stack which consists of a flat, rectangular shaped body 25 preferably of wood, or other relatively light material, shaped to fit the magazine loosely, and having a flat metal projection 26 on its under side, which is of less than half the length and width of the body 25 and is arranged at the middle of the latter close to its front edge so that, when the follower is in position on the stack of envelopes, which will be arranged, flap down, with their flaps next the front, nearly all of the weight 75 thereof will be applied to the envelopes directly over the middle of the flaps. The effect of this arrangement is not only to apply sufficient pressure to the stack to cause all the envelopes to be fed into position to be dispensed, but also, by applying excess pressure to the middle portion at the front edge, to cause or permit the end portions to be turned 80 slightly, as indicated in Fig. 7. The thickness of the fingers 24 is approximately 85 equal to that of the envelopes, and as they are held slightly above the level of the bottom 11 they support the envelopes so that their end portions are slightly upturned.

90 The machine above described is to be employed in connection with suitable coin-controlled mechanism, not shown, which prevents forward movement of the separator to an extent sufficient to deliver an envelope, unless a coin of the required denomination has been inserted, and, in connection therewith, a coin interceptor is employed which causes the return of the coin after the envelopes have been exhausted, which comprises a lever 27 arranged in one side of the magazine near its bottom, so that, while there are any envelopes in the magazine, it will be held in an inoperative position thereby, as shown in Fig. 10, and when the last envelope has been delivered the lower end of the lever 27 is permitted to swing 95 into a recess 25^a in the follower, as shown in Fig. 11, in which position its upper end will intercept any coin which is inserted and cause 100 it to be returned.

105 With the above described construction the 110 operation of delivering the envelopes is as follows: Assuming that the locking mechanism of the separator has been released and that the 115 latter is in its extreme retracted position of Figs. 2, 3, 4 and 5, the purchaser pulls on the 120 handle 23, causing the separator to be moved forward until the ends of fingers 24 are close 125 to the inner side of the front wall 1. When 130 in said retracted position, the body portion of 135 the bottom envelope rests on the top sides of 140

the fingers, the front edges 24^a of which are at a short distance in the rear of the edge of the flap of the envelope, which will ordinarily be swung down below the front edges of the fingers, so that, as the fingers are advanced 5 they will pass above the flap and engage the bottom of the fold at each end of the envelope, and, on further movement, will draw the envelope from beneath the stack and into the passage between flanges 16 and 17, thru the slot portion in recess 15, so that the purchaser 10 may grasp the middle portion thereof and draw it thru the slot. The edges of the envelope flap, as ordinarily shaped, extend obliquely from the corners to the middle, so that the beveled corners 24^b of the fingers will be passed over the flap in advance of the other portions thereof, as shown in Fig. 8. In case the flap should adhere to the body, or should lie flat thereagainst, the sharp beveled edge 20 24^b of each finger, the flat side of which bears against the body, will deflect the flap away from the body, so that, on continued movement the finger will pass over the flap, as shown in Fig. 9.

Ordinarily envelope flaps are not gummed close to their ends, and the fingers 24 are made of approximately the same width as the length of the ungummed portion thereof, so that, even if the gummed portion should 30 adhere before the envelope is dispensed, the fingers will nevertheless pass readily between the fold and body. Their entry therebetween is moreover made more certain by providing a form of follower which only applies appreciable pressure at the middle portion of the envelopes, as the fingers are thereby enabled to pass over the flap more easily. The turning up of the ends of the envelopes 35 also tends to make the flap spring away from the body, so that the fingers may more readily pass between the flap and the body, as indicated in Figs. 7 and 13.

In consequence the delivery of an envelope 40 on each reciprocation of the separator is insured.

As the return movement of the separator will preferably be caused by a spring, and as the operator is liable to release the handle 45 23 before the envelope is removed, means are provided for positively preventing the envelope from being moved back with the separator, which consist of a lug or projection 28, which is formed in the bottom, said projection having a vertical shoulder at its front 50 side arranged to engage the rear edge of the envelope when it has been moved to delivering position and prevent it from being moved backward.

With the above described construction the 55 envelope passage from the front to the magazine is of considerable length and the height thereof is only sufficient to permit the envelope to be carried or drawn therethru, and 60 by providing the recess, or depression into

which the middle portion of the envelope is carried, it is unnecessary for the delivery slot in the front wall to be enlarged beyond what is necessary to permit the envelope to be withdrawn, as no allowance has to be made for the passage of the separator fingers therethru to deliver the envelopes. Consequently pilfering of the machine, thru the delivery slot, by the insertion of an instrument, is rendered practically impossible. 70 75

I claim:

1. An envelope dispensing machine comprising a support for a stack of envelopes arranged flap down, a separator reciprocally movable beneath the stack and having a flat horizontally disposed finger projecting forwardly at each end of said support and arranged to be passed between the flap and body of the bottom envelope in the stack at each end thereof as the separator is moved forwardly, said fingers having aligned end faces for engagement with the bottom of the fold between the flap and body and having their under sides beveled to the adjacent ends of said faces to form a relatively sharp corner 80 85 portion for separating the flap from the body preliminarily. 90

2. An envelope dispensing machine comprising a casing having a horizontally disposed support for a stack of envelopes arranged with the flaps down, guide ways at each end of said support for the ends of the envelopes, a separator mounted to reciprocate in the direction of said guide ways and having a pair of flat fingers extending horizontally above and closely adjacent the surface of said support at each end thereof with their opposite side edges in proximity to said guide ways, said fingers having end faces arranged in alignment for engagement with the bottom of the fold between the flap and body of the envelopes and having the end portions thereof at their adjacent edges beveled from the under side to provide a relatively sharp corner portion for separating the flap from the body preliminarily. 100 105 110

3. An envelope dispensing machine comprising a casing having a horizontally disposed support for a stack of envelopes arranged with the flaps down, a separator forwardly movable beneath the stack having fingers arranged to project horizontally forward in position to pass between the flap and body of the bottom envelope and to engage the bottom of the fold therebetween, and a follower resting loosely on the top of the stack and exerting a constant pressure thereon, said follower comprising a device having a central under-face in a plane below its sides, the weight of said device being chiefly concentrated upon said central under-face which is arranged to engage the middle portion of the stack and to relieve the end portions thereof of substantial pressure. 115 120 125

4. An envelope dispensing machine com-

prising a casing having an upright front wall, said wall having a finger receiving depression therein and an envelope delivering slot extending thru the middle of the bottom of said depression and terminating in the wall portion at each side thereof, a magazine for holding a stack of envelopes flap down with the flap edge next the front, said magazine having its bottom disposed at a substantial distance in the rear of said wall and in substantial alignment with the bottom of the delivery slot therein to provide with said bottom a flat support for the lowermost envelope, and a separator having fingers arranged to engage the lowermost envelope on said bottom in the end portions of the fold between the flap and body thereof and reciprocally movable to and from said wall to move the envelope thru said passage to a position in which the middle portion thereof extends thru said slot into said depression.

5. An envelope dispensing machine comprising a casing having an upright front wall, said wall having a finger-receiving depression therein and a horizontally disposed envelope delivering slot extending thru the bottom thereof, a magazine within the casing having a bottom for supporting a stack of envelopes, said bottom having an extension which extends to the lower edge of said slot, an upright partition forming the front side of the magazine disposed at a distance in the rear of said front wall, a guide plate extending from the lower end of said partition to the upper side of said slot forming with said bottom extension an envelope passage leading to said slot and means for positively moving an envelope from said magazine bottom thru said passage to a position in which its front edge portion extends into said depression.

6. An envelope dispensing machine comprising a support for a stack of envelopes, a separator reciprocally movable at one end of the stack and having a pair of flat fingers projecting forward one from each end of said support and arranged to be passed between the flap and the body of the outermost envelope of the stack as the separator is reciprocated, said fingers having aligned end faces for engagement of the bottom of the fold between the flap and body, and having their sides beveled to form relatively sharp corner portions for separating the flap from the body preliminarily.

7. An envelope dispensing machine comprising a casing having a support for a stack of envelopes, guideways at each end of said support for the ends of the envelopes, a separator mounted to reciprocate in the direction of said guideways and having a pair of flat fingers extending closely adjacent to the surface of said support at each end thereof with their opposite side edges in proximity to said guideways, said fingers having end

faces arranged in alignment for engagement with the bottom of the fold between the flap and body of the envelopes and having the end portions thereof at their adjacent edges beveled to provide relatively sharp corner portions for separating the flaps from the bodies preliminarily.

In testimony whereof, I have signed my name to this specification.
